United States Patent Office

Des. 221,992

Patented Sept. 21, 1971

221,992

STEAM GENERATING APPLIANCE

Bernard B. Bluestein, Des Plaines, and Douglas G. Long, Lombard, Ill., assignors to Sunbeam Corporation, Chicago, Ill.

Filed July 13, 1970, Ser. No. 23,919

Term of patent 14 years

Int. Cl. D7—05; D15—05
U.S. Cl. D49—13

FIG. 1 is a perspective view of a steam generating appliance embodying our new design;

FIG. 2 is a side elevational view thereof;

FIG. 3 is a rear elevational view thereof;

FIG. 4 is a top plan view thereof; and

FIG. 5 is a bottom plan view thereof.

We claim:

The ornamental design for a steam generating appliance, as shown.
